Primary Examiner — Carla J Wright(74) *Attorney, Agent, or Firm* — Sheppard, Mullin, Richter & Hampton LLP(57) **CLAIM**

We claim the ornamental design for a case for an electronic communications device or the like, substantially as shown and described.

DESCRIPTION

FIG. 1 is a rear and left-side perspective view of a case for an electronic communications device or the like, in accordance with the present design.

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

The broken lines in the drawing figures form no part of the claimed design and depict portions of the case for an electronic communications device that form no part of the claimed design.

1 Claim, 7 Drawing Sheets(56)
